(57) **CLAIM**

The ornamental design for a gaming machine, as shown and described.

DESCRIPTION

FIG. 1 is a front perspective view of a gaming machine showing our new design;

FIG. 2 is a front view thereof;

FIG. 3 is a left side view thereof;

FIG. 4 is a right side view thereof;

FIG. 5 is a top view thereof;

FIG. 6 is a cross-sectional view thereof taken through line 6-6 of FIG. 2;

FIG. 7 is a front perspective view of a gaming machine showing an alternate embodiment of our new design;

FIG. 8 is a front view thereof;

FIG. 9 is a left side view thereof;

FIG. 10 is a right side view thereof;

FIG. 11 is a top view thereof; and,

FIG. 12 is a cross-sectional view thereof taken through line 12-12 of FIG. 8.

The generally rectangular region shown in solid lines inside of the cabinet represents a physical display screen. The generally rectangular region shown in solid lines outside and to the rear of the cabinet represents a virtual display. The physical and virtual displays are superimposed relative to the rectangular region on the front of the display. The broken lines depicting the remainder of the gaming machine show features that form no part of the claimed design.
